UNITED STATES PATENT OFFICE.

CLAYTON T. EAID, OF PORTLAND, OREGON.

SAFETY BUNK AND STAKE FOR LOGGING-CARS.

1,189,434.

Specification of Letters Patent.

Patented July 4, 1916.

Application filed October 19, 1914. Serial No. 867,375.

To all whom it may concern:

Be it known that I, CLAYTON T. EAID, a citizen of the United States, residing at Portland, in the county of Multnomah and State of Oregon, have invented certain new and useful Improvements in Safety Bunks and Stakes for Logging-Cars, of which the following is a specification.

My invention relates to devices for holding saw logs on railroad cars or the like, and has for its object the production of improvements in the art to which belong patents issued to me as follows: 1050929, issued January 21, 1913; 1055150, issued March 4, 1913; 1071609, issued August 26, 1913; 1112690, issued October 19, 1914.

By my present invention I am enabled to produce a reliable bunk, that is simple and durable in construction, economical to manufacture, convenient and safe to operate, and one which is not easily damaged or put out of order by accident or negligence.

What constitutes my invention will be hereinafter specified in detail and succinctly set forth in the appended claims.

In the accompanying drawings which constitute a part of the specification, Figure 1 is a perspective view of the present preferred form of embodiment of my invention. Fig. 2 is a side elevation of a portion of the subject matter of Fig. 1 on an enlarged scale, showing in dotted lines the position of the chock block with its stake after its release. Fig. 3 is an end elevation of the subject matter of Fig. 1, showing in dotted lines the position of the operating handle after its operation to release the chock block.

Referring to the numerals on the drawings, 1 indicates a beam which, in the preferred form of embodiment of my invention illustrated, comprises a base 2, and a web 1^a, preferably provided with a head 3, the term web being used to denote a projecting wall extending lengthwise of the base.

As shown the beam consists of a section of a rail such as is in ordinary use on railroads. Each beam preferably carries a pair of chock blocks 4, which, when of the crutch block form, preferred, respectively straddle the web 1^a upon which they ride and to which they are adjustably secured.

As a means for adjustably securing the chock blocks to their beam, I prefer to provide each block with legs 5 and 6 which effect the straddling of the web above referred

to, and in addition thereto, to provide means of secure but sliding engagement between each block and its beam.

The head 3 with which the web is preferably provided as specified, affords in connection with lugs 8 and 9 and a cross piece 7 upon each chock block preferred means of sliding engagement, the head being essentially a longitudinally disposed projection 65 on the beam.

The cross piece 7 rides upon the beam while the lugs 9 and 8 upon the legs 5 and 6 respectively, extending under the projection upon the web 1^a which constitutes the 70 head 3, slidably secure the chock block to the beam.

Provision being thus made for slidably securing the blocks to the beam, it remains to make provision for securing them at desired points of adjustment which may be accomplished by any suitable block lock.

By the term block lock I designate any suitable mechanism for securing a block in any position upon its beam to which it may have been adjusted. Such mechanism should preferably be adapted for operation from the end of the beam opposite to that which carries the block which it controls; and I therefore prefer to employ for the 80 purpose a rod 11 provided with a chock-block-engaging-member or elongated wing 14, that is preferably corrugated, notched or toothed as illustrated in order through rotative movement of the rod to engage and 90 disengage a projection 10 extending from each chock block.

In practice it being customary to provide each beam with two blocks, I prefer, for that reason, to provide two rods 11 for each 95 beam secured, respectively, to opposite sides of a web 1^a, as by clips 12.

Each rod 11 is preferably provided with two handles for operating it, to-wit, a handle proper 13, by which a chock block is 100 discharged by its block lock in the unloading operation, and an auxiliary handle 15 by which the rod 11 may be operated only when not under load to release its block for the purposes of adjustment.

The comparative lengths of the handles 13 and 15 are preferably adapted and limited to their respective offices.

To afford protection against accidental operation of each rod 11, I prefer to provide 110 for each handle 13 an automatic safety guard which may consist of a link 16 pivoted

to the beam as by an eye bolt 17. The link is so disposed as to fall by gravity over the bend of the handle 13 and to hold the latter against operative movement until after it is 5 lifted to free the handle.

Each member 14 may be provided with a plurality of teeth to adapt it to adjustment of its chock block to different positions, but if no adjustment is required a single tooth 10 or projection on the rod 11 will suffice to hold the chock block in place.

An important and novel feature of my present invention consists in means for combining the advantages of a bunk with those 15 of a stake, the distinction of the two devices being well understood in the art. To that end I provide a stake 18 for each chock block adapted whenever required to be united to its block, without interference with 20 the discharge of the block lock from which upon such discharge it is free to drop away. To this end, I prefer to provide each chock block 4 with a cross piece 21 in addition to its cross piece 7, and to provide for engagement therewith a stake having notches 25 19 and 20. The notch 19 is adapted to engage the cross piece 7 and the notch 20 the cross piece 21 with hook-like effect as shown in Fig. 2. By this means the stakes serve 30 through outward pressure of a load upon them to hold the load, but readily drop away from the chock block when the block is discharged.

The following is a brief description of 35 the operation of my device. The beams being by any suitable means secured, usually in pairs, upon the floor of a railroad flat-car, for example, the chock blocks may be adjusted preparatory to loading. To this 40 end it is convenient to turn the rods 11 as by aid of their respective handles 15 which are preferably provided, for the purpose of such adjustment. Each rod is rotated a sufficient distance as required to disengage 45 its member 14 from the projection 10 of its respective block. Thereupon the liberated block may be by hand slid along the beam to desired adjustment, as, for example, in contact with the leg next adjacent to it upon 50 the beams, and is there secured by reverse rotation of the rod 11 and the dropping into place over its handle 13 of the proper link 16. Upon the required adjustment and locking of all the blocks of the car, the load 55 thereof is safely secured in place ready for transportation.

To release the load the car is preferably canted toward one side. The operator goes 60 to the higher side of the car and there, with entire safety to himself, successively lifts the several links 16 and upon rotation of the several rods 11 by their respective handles 13 thereby turning their respective wings 14 toward the web 1^a, discharges the lowermost blocks 4 from engagement with their respec-

tive rods 11, with the effect of allowing the logs to descend along the inclined beams and to drop over the ends thereof.

In the operation last described each block is prevented from falling entirely away 70 from its beam, as by engagement between its lugs 9 and clips 12, as shown in Fig. 2.

What I claim, within the art described, is:

1. A bunk comprising a beam, and a chock block slidably secured thereto, in combination with a rotatable rod provided with a member adapted in its movement to directly engage and to disengage said block substantially for the purpose set forth. 75

2. The combination with a beam and a crutch block slidably secured thereto, of means detached from the block and operatively mounted on the beam for fixing the adjustment of said block on the beam at different points thereon. 80

3. The combination with a beam and a crutch block slidably secured thereto, of a movable block lock on the beam detached from the block, and means for actuating the block lock. 85

4. The combination with a beam and a crutch block slidably secured thereto, of a toothed block lock movably secured to the beam, and means for actuating the block lock. 90

5. The combination with a beam and a crutch block slidably secured thereto, of a rotatable rod upon the beam provided with a block engaging and disengaging member, and means for operating the rod. 95

6. The combination with a beam, and a slidable crutch block mounted thereon, of a rotatable toothed rod adapted to engage the block to secure it at different points on the beam. 100

7. The combination with a beam, and a chock block slidably secured thereto, of a stake detachably secured to said block. 105

8. The combination with a beam, and a chock block slidably secured thereto and 110 so as to drop below the top of the beam for unloading, of a stake secured to said block and adapted to be detached therefrom by the dropping of the block.

9. The combination with a beam, and a 115 slidable crutch block mounted thereon and adapted in unloading to drop over the end of the beam, of a detachable stake mounted on said block and adapted to be detached from the block by the dropping thereof.

10. The combination with a beam provided with a longitudinally disposed projection, of a slidable crutch block thereon provided with means for engaging the projection on the beam, and means upon the beam for 125 adjustably fixing the block upon the beam.

11. The combination with a beam provided with a longitudinally disposed projection, of a slidable block thereon, provided with legs having lugs, respectively, 130

engaging the projection on the beam, and means upon the beam for adjustably fixing the block upon the beam.

12. The combination of a beam, and a 5 slidable chock block mounted on top of and in direct pivotal connection with the beam, adjustable to different positions thereon, and arranged to pivotally drop over the end of the beam when released without severing 10 pivotal relationship with the beam.

13. The combination with a beam, a crutch block slidably secured thereto, and a block lock, of a detachable stake mounted on the block, said block and stake both being 15 simultaneously adjustable to different positions on the beam, and means to lock and release said block and stake simultaneously.

14. The combination with a beam and a 20 slidable crutch block mounted thereon toward one end thereof, of a rotatable rod mounted on the beam and adapted to engage and disengage said block, said rod extending toward the end of the beam opposite 25 to that which carries the block.

15. The combination with a beam, and a crutch block mounted on said beam, and provided with means of engagement therewith, of a toothed rod adapted to engage 30 and disengage said block.

16. The combination with a beam provided with a longitudinally disposed projection near its upper edge, and a crutch block slidably mounted on the beam, of 35 means slidably connecting the block and the projection, and a rigid block lock, substantially for the purpose specified.

17. The combination with a beam and a crutch block movably secured thereto, of 40 rigid means for discharging the block from the end of the beam opposite to that which carried the block.

18. The combination with a beam provided with a flanged block support, of a 45 crutch block adjustably secured to said support by aid of said flange and rigid means for fixing the adjustment of said block, said means being operable from the

end of the beam opposite to that which carries the block.

50

19. The combination with a beam, and an adjustable chock block, of means for fixing the adjustment of the chock block, and an automatic safety guard for said means.

20. The combination with a beam and a 55 chock block adjustable thereon, of a block lock, means for operating the same, and an automatic safety guard for said means.

21. The combination with a beam and a chock block adjustable thereon, of a block 60 lock, means for operating the same, and an automatic safety guard for said means consisting of a link as specified.

22. A bunk comprising a beam, a movable chock block, in combination with a rotatable rod adapted by its rotative movement 65 only to engage and disengage the chock block.

23. A bunk comprising a beam and an adjustable chock block, in combination with 70 a rod rotatably fixed to the beam and adapted to make direct engagement with the chock block for fixing its adjustment on the beam.

24. A bunk consisting of the following 75 elements and no more in combination to wit, a chock block supporting member, a pair of chock blocks adjustable thereon longitudinally and a rotatable block engaging rod, secured to the said supporting member.

25. A bunk comprising an adjustable chock block, and a supporting member therefor, in combination with a rotatable rod adapted to make direct engagement with 85 and to disengage the block, and means for operating the rod at one end of the supporting member to engage or disengage the block at the other end thereof.

In testimony that I claim the foregoing as 90 my own, I hereunto affix my signature in the presence of two witnesses.

CLAYTON T. EAID.
